STRIPING NEEDLE DIVIDING MECHANISM
FOR CIRCULAR KNITTING MACHINESFrank W. Robinson, Reading, Pa., assignor to
Schuylkill Hosiery Mills, Reading, Pa., a cor-
poration of PennsylvaniaOriginal application April 16, 1929, Serial No.
355,605. Divided and this application June 1,
1932. Serial No. 614,704

4 Claims. (Cl. 66—40)

My invention relates to circular knitting machines having a striping thread attachment of the nature described in my prior Patent No. 1,428,398 of September 5, 1922, and to certain improvements thereof set forth in my copending application Serial No. 355,605, filed April 16, 1929, (later Patent No. 1,864,321, issued June 21, 1932) in both of which depending guide fingers are swung radially above the circle of needles and therealong for limited distances to feed their embroidery threads to determined needles selectively raised temporarily above the remaining needles for a portion of certain complete rotations of the needle cylinders.

My present improvements form a division of my aforesaid application Serial No. 355,605 (Patent No. 1,864,321, issued June 21, 1932) and relate particularly to the improved mechanism therein disclosed for selectively raising determined needles into feeding position to receive the striping threads; the nature of such improvements and the advantages thereof being more fully described in connection with the accompanying drawing, and the novel features pointed out in the appended claims.

Fig. 1 is a diagrammatic sectional elevation indicating certain well known portions of a circular knitting machine and embodying the present improved mechanism for selectively raising temporarily, determined needles into feeding position to receive the embroidery threads fed thereto by the striping thread guides.

Fig. 2 is a corresponding part sectional elevation taken at right angles to that of Fig. 1.

Fig. 3 is a developed diagrammatic elevation of the cam ring, showing the needle lowering mechanism for certain of the raised striping thread needles.

The knitting machine, and the striping attachment indicated in the present drawings merely by a showing of two thread guide fingers 6, 6, are similar in their main features and operation to those more fully shown and described in my prior constructions previously referred to, and comprise a usual rotary needle cylinder 2, certain of the circular series of needles 3 carried thereby having operative varyingly-butted jacks 4 acted upon by a series of jack cams 5, the different movements of the latter being controlled as heretofore by pattern mechanism to selectively raise determined needles into feeding position to receive threads from the several guide fingers 6, 6, of the striping attachment, which fingers 6, 6, have imparted to them needle-engaging swinging movements controlled by pattern

mechanism, all as more fully described in my aforesaid patents.

The needles 3 each have a butt 3a for action of the usual knitting cams shown in Fig. 3, and the jacks 4 for said needles have actuating butts 60 which are divided into three series 4a, 4b, 4c, by the projection of their respective butts at different levels, and each series may be further divided by variations in the length of projection of the several butts for determined action of their respective jack cams 5a, 5b, and 5c.

The jack cams 5 are slidably mounted, as shown in Fig. 1, in a bracket 90 carried on the cam ring 76 of the knitting machine, and are normally held out of action as by springs 91, and each is determinedly projected into the path of its respective series of butts by its corresponding lever 66, intermediately pivoted at 92, with their opposite ends riding in separate paths on a cam drum 70. By the proper location of cams 93 on 75 said drum, varying in location and height in each lever path, selected cams may be projected, and the projection of each cam varied to act on more or less of the jack butts in such level according to the division in the lengths of such 80 butts.

Such controlled action of the jack cams will cause their jacks to raise their respective needles into position to receive the striping thread fed by the guides 6, 6, in accordance with the arrangement of the series of varied-butted jacks, which will be determined by the pattern desired.

The present improvements relate to means for relowering certain of said raised needles before they receive the striping thread fed by guides 6, 6, 90 so as to provide for forming interrupted stripes, or where it is desirable to entirely omit certain stripes as in the foot portion of a stocking, and the means shown in the drawing for this purpose will now be described.

As shown in Fig. 1, a cam 75 is slidably mounted in an extension of bracket 90 carried by cam ring 76, and is shiftable bodily into the path of the needle butts 3a by a pattern controlled lever 77, intermediately pivoted at 94 and its opposite end riding in a separate path on cam drum 70 and acted upon by a suitable cam or cams 71. Cam 75 has a pivotal turning movement on its shiftable bearing axle, and is formed with an eccentric needle-butt engaging cam edge 80 normally held turned in idle raised position and retracted from the path of said needle butt by coil spring 81. Cam 75 is positioned at a height adapted to normally lie just above the path of travel of the needle butts raised by action of 110

their jack cams, and when cam 75 is turned on its axle, its cam edge 80 is swung to engage said needle butts and lower them out of such raised path. When cam 75 is radially shifted toward cylinder 2 by lever 77, a projection 82 on said cam 5 is brought into the path of travel of a cam or cams 83 secured at proper position for movement with the needle cylinder, as by fixed mounting thereof on the underside of the sinker ring 10 as shown or directly on the rotating needle cylinder 2. Cam 83 for a part of each rotation of needle cylinder 2 will then engage and depress projection 82 of cam 75 so as to axially turn the latter and swing its cam edge 80 across the 15 feed level path of travel of the jack raised needles, such temporary position of said cam edge 80 relowering out of said feed level path any raised needles that engage it. The needles thus relowered will not receive a striping thread 20 in that particular cylinder rotation, but may in a succeeding rotation, depending on the action of the jack cams to raise them and the action of lever 77 to position cam 75 to lower them.

Diagrammatic Fig. 3 fully shows the action of 25 the jack cams and of relowering cam 75, and in this showing it may be assumed that cam 75 has been radially shifted inward by action of lever 77 so that cam projection 82 will be depressed by needle cylinder carried cam 83.

30 In said Fig. 3, dotted line 3b indicates the path of travel of the needle butts in the regular knitting action and receiving the main thread upon rising on the stitch cam as usual, dotted line 3m indicating the path of travel of the needle hooks 35 in the regular knitting action. Dotted line 4m indicates the path of travel of the needles raised by action of the several jack cams 5a, 5b and 5c to a level to receive thread from the guide 6. The dotted position of cam 75 shows its action, 40 when depressed by cam 83, to relower any raised needles by engaging the butts of the latter and lowering them to an intermediate non-feeding level 3n. Five needles 3 are also indicated with 45 their respective jacks: needle 3-d having its butt in the knitting path, and its jack butt in the path of jack cam 5c but not actuated thereby; needle 3-e having its butt raised into striping-feed level 4m by action of jack cam 5a on its jack butt; needle 3-f similarly raised by 50 action of jack cam 5b on its jack butt; needle 3-g also similarly raised by action of jack cam 5c on its jack butt; and needle 3-h raised by action of jack cam 5a on its jack butt, but re-lowered to intermediate level 3n by cam 75, the 55 edge 80 of the latter having engaged the needle butt.

The cam drum 70, with suitable cams properly located will determine the action of levers 66, 66, 66, and lever 77, which in turn control 60 the action of jack cams 5a, 5b, and 5c, and re-lowering cam 75 respectively, and the action of these cams determines which needles will receive the striping thread to form the particular pattern determined upon.

65 The drawing is largely diagrammatic, and it is to be understood that the specific needle division effected by the eccentric cam may be employed in connection with other requirements of thread feed or needle manipulation.

What I claim is:

1. In combination with a circular knitting machine comprising a needle cylinder, needles in said cylinder having operating butts, actuating jacks for said needles having operating butts, cams operative on selected jack butts to dividingly raise their respective needles, above the other needles, a cam selectively positionable for action on the butts of said raised needles, and a cam operative with the needle cylinder and actuating said positionable cam at each cylinder rotation when said positionable cam is in acting position to relower selected ones of the raised needles to withdraw them from the division effected by the cams selectively active on the jack butts. 80 90

2. In combination with a circular knitting machine comprising a needle cylinder and operative cam mechanism, a guide member having needle feeding movements, needle jacks, cam selectively operative on said jacks in determined cylinder 95 rotations to raise their respective needles for traverse during a part of said determined cylinder rotations at a guide-feed receiving level, and pattern controlled needle-engaging cam mechanism operative during certain of said part cylinder rotations to relower out of said guide feed receiving level selected jack raised needles. 100

3. In combination with a circular knitting machine comprising a needle cylinder and operative cam mechanism, a guide member having needle 105 feeding movements, needle jacks, cams selectively operative on said jacks in determined cylinder rotations to raise their respective needles for traverse during a part of said determined cylinder rotations at a guide-feed receiving level, an operative cam for said jack raised needles, pattern controlled mechanism for operatively positioning said cam in determined cylinder rotations, and a cam operatively carried by said cylinder for actuating said positioned needle operative cam 110 during a cylinder rotation to relower out of said guide feed receiving level selected jack raised needles. 115

4. In combination with a circular knitting machine comprising a needle cylinder and operative 120 cam mechanism, and a guide member having needle engaging movements, a circular series of needles having operating butts, a corresponding series of needle actuating jacks divided into pre-determined groups by group butts of varying 125 lengths and at varying levels, jack cams for each butt level and pattern controlled mechanism for selectively moving each cam for action on determined butt groups to raise their respective jack needles for traverse during a part of determined 130 cylinder rotations at a guide-feed receiving level, an eccentric cam operative on the butts of said jack raised needles, a pattern controlled lever for operatively positioning said eccentric cam in determined cylinder rotations, and a cam opera- 135 tively associated with said needle cylinder and acting during a part of each cylinder rotation to eccentrically position said needle butt operative cam when operatively positioned by said pattern controlled lever so as to relower out of said 140 guide feed receiving level selected ones of the jack raised needles.

FRANK W. ROBINSON.
